UNITED STATES PATENT OFFICE

GEORGE HILGER, OF CHICAGO, ILLINOIS

CONDENSER

Application filed November 18, 1929. Serial No. 407,828.

The present invention relates to improvements in condensers, particularly gas condensers adapted for use in mechanical refrigerating systems.

Gas condensers may be of various types, but in general may be said to comprise a wall of heat conducting material presenting relatively extensive surfaces for effecting the exchange of heat from a medium to be cooled and liquefied to a cooling medium. In mechanical compression refrigeration, the first medium is the refrigerant, and the second medium preferably is cold water. The refrigerant employed preferably has a low boiling point at ordinary temperatures and a high latent heat value. The most common refrigerants are ammonia, carbon-dioxide, sulphur-dioxide, ethyl-chloride and methyl-chloride.

In normal operation, the refrigerant enters the top of the condenser as a highly superheated gas. The cooling medium is also supplied to the top of the condenser. The superheat in the gas thus is rapidly removed in the initial or upper part of the condenser. Thereafter, because of a substantially reduced temperature head the cooling action is sluggish. It has therefore been considered necessary to use condensers of substantial size so as to insure sufficient time and cooling contact to obtain complete liquefaction of the refrigerant. Such condensers have large lazy areas, obviously are cumbersome and take up a large amount of space, and are relatively expensive in construction.

An important object of the present invention resides in the provision of a new and improved condenser which is much smaller in size for a given load than has been necessary heretofore to insure complete liquefaction, and yet is efficient and quick in operation, and which comprises no sluggish or lazy areas but is effective and substantially uniform in efficiency throughout the extent of the cooling area.

A more specific object of the invention resides in the provision of a novel condenser comprising means for injecting cold but unliquefied gas from a lower portion and preferably the discharge end of the condenser into

the incoming gas so as to remove the superheat without taxing the initial area of the condenser.

Further objects and advantages will become apparent as the description proceeds. 55

In the accompanying drawings:

Fig. 1 is a fragmentary side elevational view, with the inlet manifold in transverse section, of a condenser embodying the features of my invention. 60

Fig. 2 is a fragmentary horizontal view, partially in section and taken along line 2—2 of Fig. 1.

Fig. 3 is a view similar to Fig. 1 of a modified form of the invention. 65

Fig. 4 is a fragmentary horizontal sectional view taken along line 4—4 of Fig. 3.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims. 70

Referring more particularly to the drawings, I have for purposes of illustration shown the invention embodied in a condenser of the coil type which is adapted to be used advantageously in an ammonia compression refrigerating system. It is to be understood, however, that the invention is not limited to the particular type of condenser employed or to the specific refrigerant used. 80

In the preferred form, the condenser comprises a plurality of flat sinuous coil units 10—15 which are disposed vertically in closely spaced parallel relation. The upper ends of the units 10—15 constitute the inlet ends, and for purposes of distribution are suitably connected to a manifold 17 in turn adapted to be connected through a pipe 18 to a gas compressor (not shown). The lower ends of the units 10—15 discharge to a header 16 adapted to be connected through a liquid discharge pipe 19 to a suitable liquid receiver 26. 90

Preferably water is used as the cooling me- 100

dium, and means is provided for causing the water to pass downwardly over the coil units. To this end, a plurality of water pans 20—25 are mounted over the respective units along the top pipes. Each of these pans is adapted to receive water from any suitable source (not shown), and has a perforated bottom wall 27 for discharging the water to the top of the unit. A suitable drip pan 28 extends below the units 10—15 in position to catch the water dripping from the lower ends thereof.

The construction thus far described is old and well known, and taken by itself forms no part of the present invention. If this construction alone were used, gas would enter the top pipes of the units 10—15 in a highly superheated condition. Due to the high temperature difference between the gas and the cooling medium at this point, the cooling action in the top pipes would be very active and most or practically all of the superheat in the gas would be removed. As a result, the cooling action in the lower pipes would be sluggish, and unless the condenser were extensive in area, the gas would not be liquefied expeditiously or completely.

An important feature of the present invention resides in utilizing any unliquefied gas from a lower portion and preferably the lower end of the condenser to absorb the high head of heat in the incoming gas so as not to place such a high load on the top portion of each condenser unit, but on the contrary to distribute the load more uniformly over the entire condenser. To this end, a vertical partition wall 29 is provided in the manifold 17, and divides the latter into two substantially equal longitudinal chambers 30 and 31. The supply pipe 18 opens to the chamber 30, and the inlet ends of the coil units 10—15 open from the side of the chamber 31. Suitably mounted in and opening through the partition wall 29 are a plurality of injector nozzles 32, one for each coil unit. The injector nozzles extend a short distance into the inlet ends of the coil units, but in spaced relation to the walls thereof so as to define annular spaces for the intake of gas from the chamber 31. Branching upwardly from the lower ends of the coil units 10 to 15 are a plurality of riser pipes 33—38, the upper ends of which open to the chamber 31.

In operation, the incoming gas which usually is highly superheated is discharged from the chamber 30 through the nozzles 32 into the coil units 10—15 thereby producing a relatively low pressure in the chamber 31 and the pipes 33—38. As a result, cooled unliquefied gas from the discharge ends of these units is drawn upwardly into the manifold 17 and then into the inlet ends of the coil units where it is intermingled with the superheated gas, and serves to absorb the superheat. The cool recirculated gas thus materially reduces the temperature of the gas

mixture, and therefore the initial temperature head between the mixture and the cooling medium. Hence, the excessive load, normally on the top portion of the condenser and serving to increase substantially the initial temperature of the cooling medium, is eliminated, and the cooling action is active and more nearly uniform throughout the entire length of the condenser. No lazy areas exist. I have found that condensers constructed in accordance with my invention can be reduced approximately fifty per cent in size from the size ordinarily employed without reducing its capacity or efficiency.

The modified form of the invention shown in Figs. 3 and 4 is similar to the form shown in Figs. 1 and 2, and corresponding parts are therefore identified by like reference characters. In the modified form, a plurality of spaced depending supplemental supply pipes 39—44, one for each of the coils 10—15, open from the chamber 30. Each of these pipes is adapted to be connected with the adjacent condenser coil at one or more intermediate points along the latter. In the present instance, each of the pipes 39—44 is connected through a plurality of branch pipes 45 respectively to the lower legs of the adjacent bends of the refrigerant coil. The branch pipes 45 open to the coil in the direction of flow, and preferably are provided respectively with restricted discharge nozzles 46.

It will be evident that each of the pipes 45 with the nozzles 46 constitutes an injector which is effective to boost the pressure in the coil at an intermediate point, and to induce the downward flow of refrigerant. The speed of flow through the condenser thus is increased and the normal pressure drop from the top to the bottom is substantially diminished. By reason of the relatively higher pressure which will exist in the header 16 as a result of these successive boosts, a greater pressure drop from the header 16 through the chamber 31 to the primary inlet of the coil will exist, and hence a greater flow of gas through the riser tubes will result. In general, the rate of flow through the condenser will be increased, and the load will be distributed still more uniformly through the entire length.

I claim as my invention:

1. A condenser comprising, in combination, a plurality of flat sinuous cooling coils vertically arranged in parallel spaced relation, a closed cylindrical manifold extending transversely of said coils, a longitudinal vertical partition in said manifold and defining two separated chambers therein, a line for supplying gas to one of said chambers, riser lines branching from the discharge ends of said coils and opening to the other of said chambers, the inlet ends of said coils opening to the side of said other chamber, and a plurality of tapered injector nozzles mounted in

and opening through said partition, the free ends of said nozzles extending through said other chamber in spaced relation into the inlet ends of said coils.

- 5 2. A condenser comprising, in combination, a plurality of vertical cooling coils, a closed elongated manifold extending transversely of said coils, a longitudinal partition in said manifold and defining two separated chambers therein, a line for supplying gas to one of said chambers, riser lines branching from the discharge ends of said coils and opening to the other of said chambers, the inlet ends of said coils opening to said other chamber, 10 and a plurality of injector nozzles mounted in and opening through said partition, the free ends of said nozzles extending through said other chamber in spaced relation into the inlet ends of said coils.
- 15 3. A condenser comprising, in combination, a plurality of vertical cooling coils, a manifold, a partition in said manifold and defining two separated chambers therein, a line for supplying gas to one of said chambers, lines branching from the lower portions of said coils and opening to the other of said chambers, the inlet ends of said coils opening to said other chamber, and a plurality of gas supply means mounted in and opening 20 through said partition, the free ends of said means extending through said other chamber in spaced relation into the inlet ends of said coils.

- 35 4. A condenser comprising, in combination, a plurality of cooling units, a manifold extending transversely of said units, a longitudinal partition in said manifold and defining two separated chambers therein, a line for supplying gas to one of said chambers, 40 means branching from the discharge of said units and opening to the other of said chambers for supplying uncondensed gas thereto, the inlets of said units opening to said other chamber, and a plurality of injector nozzles 45 opening from said first chamber through said other chamber in spaced relation into the inlets of said units.

5. A condenser comprising, in combination, a plurality of cooling units each having an inlet end and a discharge end, means for supplying gas to said inlet ends, and means for supplying gas from said discharge ends to said inlet ends.

6. A condenser comprising, in combination, a flat vertically disposed sinuous cooling coil, means for discharging a cooling medium over the top of said coil, a first gas chamber communicating with the inlet end of said coil, a riser pipe branching from the discharge end of said coil and opening to the bottom of said chamber, a second gas chamber, and a discharge nozzle opening from said second chamber through said first chamber in spaced relation into the inlet end of said coil.

7. A condenser comprising, in combination, a vertically disposed cooling coil, means for discharging a cooling medium onto said coil, a gas chamber communicating with the inlet end of said coil, a pipe branching from the lower portion of said coil and opening to said chamber, and a discharge nozzle opening through said chamber in spaced relation into the inlet end of said coil. 70

8. A condenser comprising, in combination, a cooling unit having an upper inlet end and a lower discharge end, means for cooling said unit, a chamber communicating with said inlet end, a line connecting a lower portion of said unit to said chamber, and means extending through said chamber in spaced relation into said inlet end for discharging gas thereto. 75

9. A condenser comprising, in combination, a vertical coil having an inlet end at the top and a discharge end at the bottom, a branch riser line connecting said ends, and means for injecting gas under pressure into said inlet end, whereby unliquefied gas in said discharge end is drawn upwardly through said line into said inlet end and mingled with the injected gas. 80

10. A condenser comprising, in combination, a vertical cooling unit having a gas inlet and a liquid discharge, a cross line connecting a point near said inlet of said unit with a point near said discharge, and means for supplying gas under pressure into said inlet, whereby unliquefied gas from said unit will be drawn through said line into said inlet 90 and mingled with the pressure gas. 95

11. A condenser comprising, in combination, means defining heat exchange surfaces for transferring heat from a medium to be cooled to a cooling medium, means for supplying gas to said first mentioned means, liquid discharge means for said first mentioned means, and means for automatically injecting gas from said discharge means into the incoming gas. 105

12. A condenser comprising, in combination, heat exchange means defining a closed path for the gas and its condensate, said means having a primary inlet at one end of said path and a discharge at the other end of said path and having a plurality of supplemental inlets at intermediate points along said path and opening in the direction of flow, means for supplying gas to said inlets, means for removing liquid from said discharge, and means for returning gas from said discharge to said primary inlet to mingle with the incoming gas. 110

13. A condenser comprising, in combination, heat exchange means defining a closed path for the gas and its condensate, said means having a primary inlet at one end of said path and a discharge at the other end of said path and having a plurality of supplemental inlets at intermediate points along 115

said path and opening in the direction of flow, means for supplying gas to said inlets, and means for removing liquid from said discharge.

14. A condenser comprising, in combination, a plurality of flat sinuous cooling coils vertically arranged in parallel spaced relation, a closed cylindrical manifold extending transversely of said coils, a longitudinal partition in said manifold defining two chambers therein, a line for supplying gas to one of said chambers, riser lines branching from the discharge ends of said coils and opening to the other of said chambers, the inlet ends of said coils opening to the side of said other chamber, a plurality of injector nozzles opening from said one chamber through said partition into the inlet ends of said coils, a plurality of depending lines one for each coil opening from said one chamber, and a plurality of branch supply lines opening from each depending line to the lower legs of the adjacent bends in each coil, and discharging thereto in the direction of flow.

15. A condenser comprising, in combination, a cooling unit disposed in a generally vertical position, means for supplying a condensable gas to the upper end of said unit, supplemental means for supplying said gas to intermediate points along said unit, and means for recirculating unliquefied gas from the lower portion of said unit to the upper portion of said unit.

16. A condenser comprising, in combination, a flat vertically disposed sinuous cooling coil, means for discharging a cooling medium over the top of said coil, a first gas chamber communicating with the inlet end of said coil, a riser pipe branching from the discharge end of said coil and opening to the bottom of said chamber, a second gas chamber, a discharge nozzle opening from said second gas chamber through said first chamber into said inlet end of said coil, and discharge means for connecting said second gas chamber to said coil at a plurality of intermediate spaced points along its length.

17. A condenser comprising, in combination, a vertically disposed cooling coil, means for discharging a cooling medium over said coil, a gas chamber communicating with the inlet end of said coil, a pipe branching from the discharge portion of said coil and opening to said chamber, injector means in communication with said chamber for supplying gas under pressure into said inlet end of said coil, and supplemental injector means for supplying gas under pressure to said coil at an intermediate point and in the direction of flow.

18. A condenser comprising, in combination, a cooling unit defining a closed path, means for supplying a gas under pressure to the inlet end of said unit, and supplemental injector means for supplying gas under pres-

sure to said unit at an intermediate point in said path, said injector means discharging generally in the direction of flow along said path.

19. For use in a condenser comprising a cooling unit having an inlet at one end and a discharge at the other end, the method of condensing a gas which consists in supplying superheated gas to said inlet, abstracting heat from said gas in the course of its passage through said unit to condense a substantial portion of said gas, and injecting gas from the cooled uncondensed portion into said inlet to absorb the high heat of heat in the incoming superheated gas.

20. A condenser comprising, in combination, means defining heat exchange surfaces for transferring heat from a medium to be cooled to a cooling medium, means for supplying gas to said first mentioned means, liquid discharge means for said first mentioned means, and means for automatically recirculating uncondensed gas from a relatively cold region in said first mentioned means back to a relatively hot region in said first mentioned means.

21. A condenser comprising, in combination, heat exchange means defining a closed path for the gas and its condensate, said means having a primary inlet at one end of said path and a discharge at the other end of said path and having a supplemental inlet at an intermediate point along said path, means for supplying gas to said inlets, and means for removing liquid from said discharge.

22. For use in a condenser comprising a cooling medium having an inlet at one end and a discharge at the other end, the method of condensing a gas which consists in supplying superheated gas to said inlet, abstracting heat from said gas in the course of its passage through said unit to condense a substantial portion of said gas, and introducing by recirculation uncondensed gas from a point of relatively low temperature into the gas at a point of relatively higher temperature.

In testimony whereof, I have hereunto affixed my signature.

GEORGE HILGER.
